UNITED STATES PATENT OFFICE.

HENRY A. RUETER, OF BOSTON, MASSACHUSETTS.

TAP-HOLE BUSHING AND PLUG.

SPECIFICATION forming part of Letters Patent No. 293,278, dated February 12, 1884.

Application filed February 26, 1883. (No model.)

To all whom it may concern:

Be it known that I, HENRY A. RUETER, of Boston, in the county of Suffolk and Commonwealth of Massachusetts, have invented a new and useful Improvement in Bushings and Stoppers for Tap-Holes in Casks for Ale and Beer, of which the following is a specification.

My invention relates to the form in which the bushing, or tap-hole, if no bushing is used, is made, and to the form of the stopper, the object of the invention being to provide a bushing and stopper for tap-holes in ale and beer casks, which will be entirely secure against the pressure in the inside of the cask, and which will admit the insertion of the faucet and driving it to its place without any escape of the contents of the cask, and preserve from injury by use the faucet, the bushing, or the tap-hole when no bushing is used; and it consists in making the hole through the bushing to be inserted in a tap-hole, or of the tap-hole, if no bushing is used, one-half of its length next the outside of the cask in form of a cone-frustum, or in the form of a frustum or zone of a spheroid, increasing in diameter from the middle, or the line where the change of form begins, toward the outer end, and the other half of its length next the inner side head-piece or stave of the cask in the form of a cylinder having at its extreme inner end a short bevel from the inside surface to the outside surface of the bushing, or, if no bushing is used, a bevel in the wood of the cask; and in making the stopper with an outside form about half its length at the outer end a cone-frustum or a frustum or zone of a spheroid, and about half its length at the inner end in form of a cylinder, and with a chamber in the center of its outer end large enough in diameter to admit the end of a faucet, and as deep as the line across it, where the cone or spheroid frustum and the cylinder forms meet, and with a narrow cut around its circumference, about opposite the line mentioned, perpendicular to its central axial line, and on or nearly on a plane with the bottom of the chamber, and extending about half-way from the outer surface of the stopper to the bottom of the chamber.

In the drawings annexed, Figure 1 shows a vertical sectional edge view of the metallic bushing, with its outer end in the form of a

cone-frustum. Fig. 2 shows the same, with its outer end in form of a spheroid frustum, and the tap-hole stopper in it. Fig. 3 shows a vertical sectional view of the stopper, and the chamber in the center of its outer end, and the cone-frustum form. Fig. 4 shows the same as Fig. 3, with the spheroid-frustum form. Fig. 5 shows a section of a head or stave piece of a cask, a metallic bushing in it, a section of the outer end of the stopper, the inner end of the stopper broken off and pushed out of the bushing, and a faucet driven to its place in the bushing and in the wooden packing formed by the outer chambered end of the stopper. Fig. 6 shows a device for use in placing the stopper or plug in its place in the tap-hole, or in the bushing in the hole made for it.

a is the metallic bushing.

a' is the cone-frustum-shaped end of the bushing.

a'' is the spheroid-frustum-shaped outer end of the hole through bushing.

a''' is the cylinder-shaped end of the hole through bushing.

a⁴ is the bevel on the inner end of the bushing.

a⁵ is the cylindrical-shaped end of the tap-hole stopper.

a⁶ is the spheroid-frustum-shaped outer end of the tap-hole stopper.

a⁷ is the cone-frustum-shaped outer end of the tap-hole stopper.

a⁸ is a transverse cut in the stopper entirely around its circumference on a line in or nearly in the plane of the bottom of the chamber in the outer end of it, the depth of which is such as to leave about one-eighth to one-sixteenth of an inch of uncut wood between it and the bottom of the chamber. The purpose of this transverse cut is to so nearly sever the plug in the middle into two parts that when the faucet is driven into its place it will break the end of the stopper off from the outer chambered end of it, and force the inner end of it into the cask.

a⁹ shows the wall of the chamber *c*, after the inner end of the tap-hole stopper is broken from it by drawing the faucet into its place.

c shows the expansion of the inner end of the stopper, which the bevel on the inner end of the bushing or tap-hole admits, and which forms a head, which is pressed against the

bevel on the bushing or tap-hole, and renders the stopper secure against being driven out by the pressure within the cask.

5 c^1 is the wood of the head-piece or stave of the cask.

c^2 is the entering end of the faucet.

10 c^3 is the chamber in the center of the outer end of the stopper. This chamber will be of a diameter to admit the entering end of the faucet, generally about three-quarters of the diameter of the cylindrical end of the stopper, and its depth will reach about to the line of meeting of the cone or spheroid frustum and cylinder forms of the outside of the stopper.

15 The object of the central chamber in the outer end of the stopper is to allow the faucet to enter into the stopper about half of the length of the stopper, and to form a packing around the faucet to prevent its coming in contact 20 with the bushing, or with the tap-hole, if no bushing is used.

25 c^4 is a follower, the smaller part of which is of a diameter which will allow it to enter the chamber in the outer end of the stopper, and reach to and against the bottom of the chamber, so that the shoulders formed by the larger end of the follower will rest on and against the outer end of the stopper. The purpose for which this follower is used is to drive the 30 stopper to its place in the bushing or tap-hole.

If no metallic bushing is used, the tap-hole will be reamed out with an instrument suitable for that purpose, so as to give the inside of it the form described as the inside form of the bushing. When the stopper is driven into 35 its place in the bushing, the inner end of it will immediately expand in the bevel in the inner end of the bushing or tap-hole, so that it cannot be forced out by the pressure inside 40 the cask.

When the faucet is to be put into place for use in the cask, the entering end being placed in the chamber c^3 , a forcible blow of a ham-

55 mer on the outer end of the faucet will send it to its place, breaking off the inner end of 45 the stopper and carrying it into the cask, the walls of the chamber c^3 , which form the packing a^3 between the faucet and the inside of the bushing, will be retained between the faucet and the bushing, and will prevent the escape 50 of fluids from the cask. When the cask is empty and to be filled again, the faucet will be loosened and withdrawn, and the wooden packing a^3 will be split and drawn out, and a new stopper will be inserted.

If the tap-hole stopper is made with the grain of the wood transversely across it, the transverse cut a^8 may be dispensed with, as the cylindrical end of the stopper will readily split off from the cone-frustum-shaped end 60 when the faucet is driven in.

I am aware of the several patents for bungs heretofore issued to Pentlarge, Fountain, Pentlarge and Hursch, Borst, Pentlarge, Brown, Shaw, and H. H. Rueter; but I do not claim 65 anything described and claimed by either of them, or by any others; but

I do claim as new and my invention—

1. The combination of a cask having a tap-hole of a frustum of conical or spheroidal form 70 about half the length of the hole from the outer end of it, and of cylindrical form the remainder of the length of the hole to the inner end thereof, and a tap-hole stopper of a form corresponding to the form of the tap-hole, substantially as set forth.

2. A tap-hole stopper having the chamber c^3 and the transverse cut a^8 , substantially as set forth.

3. A cask having a tap-hole provided with 80 the short bevel a^4 at its inner end, substantially as described, for the purpose set forth.

HENRY A. RUETER.
